Floyd F. Cary INVENTOR

Albert Malcomson
ATTORNEY

UNITED STATES PATENT OFFICE.

FLOYD F. CARY, OF FAIRHAVEN, MASSACHUSETTS, ASSIGNOR TO THE PAIRPOINT CORPORATION, A CORPORATION OF MASSACHUSETTS.

DESIGN FOR A GLASS PLATE OR SIMILAR ARTICLE.

50,550.

Specification for Design.

Patented Apr. 3, 1917.

Application filed January 7, 1916. Serial No. 70,883. Term of patent 7 years.

To all whom it may concern:

Be it known that I, FLOYD F. CARY, a citizen of the United States, residing at Fairhaven, in the county of Bristol, State of Massachusetts, have invented a new, original, and ornamental Design for a Glass Plate or Similar Article, of which the following is a specification, reference being had to the accompanying drawing, forming a part thereof.

The figure of the drawing is a plan view of my design.

The center of the design comprises a rosette A, surrounded by circles B, from the outer circumference of which extend radial figures C, C, to an outer border D. A

draped wreath F crosses the radial figures C, C, and within the wreath are circular figures G, G.

While I usually apply my design to glass articles by cutting, the same effect to a certain extent, may be secured by molding and I do not wish to limit my claim to impressing the design by cutting.

What I claim is:

The ornamental design for a glass plate or similar article, substantially as shown and described.

FLOYD F. CARY.

Witnesses:

FRED. R. FISH,
B. G. TRIPP.
